United States Patent Office

Des. 191,206
Patented Aug. 29, 1961

191,206

TELEVISION CONTROL PANEL OR SIMILAR ARTICLE

Bryce C. Bateman, Northridge, and Edward G. Beyer,
Pacific Palisades, Calif., assignors to Packard-Bell Elec-
tronics Corporation, Los Angeles, Calif., a corporation
of California

Filed Apr. 4, 1960, Ser. No. 60,016

Term of patent 14 years

(Cl. D26—14)

FIGURE 1 is an exploded perspective view of a television control panel or similar article showing our new design; and

FIGURE 2 is a front elevational view thereof.

We claim:

The ornamental design for a television control panel or similar article, substantially as shown.
